UNITED STATES PATENT OFFICE.

SAMUEL W. TAYLOR, OF BALTIMORE, MARYLAND, ASSIGNOR TO THE CROWN CORK AND SEAL COMPANY OF BALTIMORE CITY, A CORPORATION OF MARYLAND.

BOTTLE-CAPPING APPARATUS.

1,392,980.

Specification of Letters Patent. Patented Oct. 11, 1921.

Application filed November 14, 1917. Serial No. 202,015.

To all whom it may concern:

Be it known that I, SAMUEL W. TAYLOR, a citizen of the United States, residing at Baltimore, and State of Maryland, have invented certain new and useful Improvements in Bottle-Capping Apparatus, fully described and represented in the following specification and the accompanying drawings, forming a part of the same.

0 This invention relates to bottle capping apparatus, and more particularly to the means by which caps, such as crown corks, are supplied to the capping mechanism.

5 In bottle capping apparatus, particularly that type in which the capping mechanism has an orbital movement with respect to the chute, and in which crown holding means is provided, it sometimes happens that a crown, fed from the chute, usually by 20 gravity, is not properly positioned in the capping mechanism.

It is one of the objects of the invention to provide capping apparatus such that the caps are properly positioned in the capping 25 mechanism.

It is a further object of the invention to provide capping apparatus such that no damage to the machine and interruption to its operation will result in case any of the 30 relative movements of the parts take place out of their normal path or period of movement.

With these general objects in view the invention consists in the combinations, details of construction and arrangements of parts which will first be described in connection with the accompanying drawings and then more particularly pointed out.

In the drawings—

40 Figure 1 is a vertical cross-sectional view, showing parts in side elevation, of capping apparatus embodying the invention;

Fig. 2 is a view of the same in horizontal cross-section;

45 Fig. 3 is a view in side elevation, with parts in section, of the delivery end of the chute and a portion of the capping mechanism;

Fig. 4 is a view in end elevation of the 50 delivery end of the chute;

Fig. 5 is a view in vertical section through the parts shown in Fig. 3;

Fig. 6 is a cross-sectional view taken on the broken line 6—6 of Fig. 5;

Fig. 7 is a similar view taken on the line 55 7—7 of Fig. 5, and

Fig. 8 is a detail view showing, in horizontal section with parts broken away, a portion of the chute structure.

The structure here illustrated as an exemplification, comprises a crown supply chute and a plurality of capping mechanisms having an orbital and a vertical movement with respect to the chute. The capping mechanisms may be of any suitable construction, their specific structure forming, in itself, no part of the present invention except as hereinafter may appear.

Referring to the drawings, and more particularly Fig. 1, the capping mechanisms here shown as an example are carried by a cage comprising an upper spider 10 and a lower ring 11 connected by posts 12. As shown, the apparatus includes three capping plungers 13, each one of which has secured to its lower end a throat carrier 14 which carries the throat ring or capping die 15, and a bell-mouthed crown platform 16.

These plungers are slidable in upper bearings 17 carried by a bearing plate 18 and lower bearings 19 carried by a plate 20. These plungers 13 are hollow cylinders containing certain parts of the capping mechanism and they are arranged in the present embodiment to be moved vertically, so that, as the cage rotates, they in turn move downward to cap a bottle.

To this end, as here shown as an example, secured to each plunger is a pair of rack bars 21, each pair facing a corresponding pair of racks 22 on an abutment block 23 mounted on the central shaft 24. Each plunger passes slidably through an opening in a corresponding head 25 extending inward radially from a yoke 26 having upward and downward extending guide portions 27, 28. The upward extending guide portion 27 of each yoke is vertically movable in the top bearing plate 18. The other guide portion 28 extends into a cylindrical portion 29 carried by the bottom plate 20. Each yoke carries a pair of rollers 30, 31. The lower roller 30 rotates on a stud 32 carried by the yoke and the upper roller 31 is

mounted on a stud 33. These rollers ride against a circular cam track 34 which has about two-thirds of its upper and lower cam surfaces in horizontal planes while 5 slightly less than one-third is a depressed portion. By this arrangement there are always two sets of rollers on the horizontal portion of the track while the third set is on the depressed portion to operate the 10 plunger.

In the present embodiment, each head 25 of the three yokes carries a pair of journals on which are mounted pinions 38, each pair of pinions meshing with the racks 21 of the 15 corresponding plunger and a pair of racks 22 of the abutment block. As the cage rotates, and as the rollers 30, 31 run down the depressed portion of the cam, the heads 25 carry their pinions 38 downward. The tendency of this motion is to lower both plunger and abutment block, but movement of the latter is opposed within a predetermined limit, as follows: The upper end of the 20 abutment block is secured to a spider 39. To the top spider 10 of the cage is secured a depending spring hanger bar 40 surrounded by a tube 41 in the bottom of which is a bushing 42 which bears against a nut 43 on the bar 40. Bearing against the bushing is 25 a spring 44, the upper end of which bears against an arm 45 of the spider 39. When the pinions 38 are moved downward, as long as the corresponding plunger meets with resistance less than the predetermined pressure, the abutment block is held stationary 30 and the pinions rotate, thus lowering the plunger. In case an extra long bottle is encountered, excessive pressure is set up between the capping mechanism and the bottle, 35 with the result that thereafter, during the down stroke of the pinion, the abutment block is lowered against its spring, the plunger remaining stationary, so that predetermined pressure on the bottle is not exceeded. As the abutment block is moved 40 downward in this compensating operation, it tends to move the pinions of the other two plungers so as to give the latter a slight upward vertical movement from their normal 45 position.

To rotate the cage, and hence to give an orbital movement to the three capping mechanism, in the exemplification shown, an annular gear 47 is secured to the bottom ring 55 11 of the cage and this gear meshes with a pinion 48, meshing in turn with a pinion 49 on a shaft 50 which is driven in any suitable manner.

In the present embodiment, each crown 60 platform 16 is cut away on one side, as shown more clearly in Fig. 5, to permit admission of a crown from the supply chute. This leaves, in effect, a semi-circular, open chamber 51, into the embrace of which the 65 crowns fit when in capping position and

beneath each chamber protrudes the corresponding portion of the bell-mouthed portion of the part 16, in the form of a lip 52. Between the crown platform chambers are stop plates 151 arranged to prevent the flow 70 of crowns from the chute except at such times as one of the crown platforms is in crown-receiving position.

Within each plunger 13 of the present embodiment is a spring-pressed presser rod 53 75 for providing pressure on the crown during capping and holding down the bottle as the plunger rises. Each of these presser rods has associated therewith means for holding in place caps delivered from the chute. In 80 the lower end of each rod is formed a bore 54 which carries a small ball 55 being on a pin 56 and yieldably pressed downward by a small spring 57. It will be seen that a crown, in order to take its position, must 85 slide under this spring-pressed ball (Fig. 5).

The crown supply chute 60 has its upper end in register with the outlet of a source of crown supply indicated at 161 and requiring no description here. This chute is 90 carried for example by a supporting arm 61 bolted to the frame of the machine. To this end, near its upper portion, the chute is embraced by a bracket 162 in pivotal connection with the arm 61, so that the position 95 of the chute may be adjusted. At its lower end the chute of the present embodiment seats between two blocks 62, 63 formed with a passageway serving as a continuation of the crown passage, these blocks being secured to the supporting arm by bolts or screws 64. In the form here shown, associated with the chute in a manner herein-after described is a terminal lip 65 which extends (Fig. 5) into the recess of the capping mechanism formed by the open face of the crown platform chamber, so as to form substantially an unbroken path for the crowns from the chute proper to the crown 100 platform. 110

Crowns slide down the chute and into the capping mechanism, as the latter takes up the proper position, by gravity. It sometimes happens, particularly in view of the fact that the crowns must pass under the 115 spring-pressed ball 55, that gravity and the pressure of the succeeding crowns are not sufficient to properly position the crowns in the platform chamber.

Means is provided for positively acting on 120 crowns fed from the chute to center them in position in the platform chamber of the throat carrier, and in structures embodying the invention to the best advantage, this is accomplished by a wiper located beyond 125 the chute so as to lie in the path of uncentered crowns and be engaged by such crowns, as the capping head carries them past, this wiper being yieldable to release jammed crowns. Although capable of va- 130

rious constructions, in that here shown as an example, mounted as hereinafter described, is a crown wiping latch 66. As appears, for example, in Fig. 6, the wiper 66 is formed with an elbow embracing the end of block 63 against which it normally bears. As will be clear from the drawings, the wiper 66 here shown, has a guiding face substantially parallel with the chute and a 10 crown wiping face oblique to the chute. As indicated in the drawings, these crown engaging faces are offset to allow for the crown skirts, and the corners are rounded to prevent crowns from catching thereon.

15 Means is provided for yieldably mounting the wiping latch 66. Although capable of various constructions, as here shown, the wiper 66 is secured to a pivotal pin 67 mounted to swing in a bearing sleeve 68 20 formed on one side of a bracket 69 which is carried by the supporting arm in a manner hereinafter described.

The upper end of the pivotal pin 67 has a cam face 71 engaged by the foot 72 of a 25 plunger 73 pressed against the cam face by a spring 74 inclosed in a sleeve 75 having at its outer end a thumb nut 76. This sleeve is threaded into an eye socket 77 on the bracket 69 and the spring pressure may be 30 adjusted by movement of the sleeve in the socket.

As appears in the drawings, the wiper 66 extends into the path of any crown not properly centered in the chamber 51 of platform 16 and it is normally but yieldably held in this position by the spring and the parts just described. As the capping mechanisms rotate in the direction of the arrow (Fig. 2), a crown received by the throat, if 35 not properly centered, engages the wiper 66 as it passes and is forced thereby into proper position, the pressure on the crown being sufficient to cause it to pass under and displace the spring-pressed member 40 45 if each member is present in the capping mechanism. Should a crown become jammed between the wiper and any part of the throat, the resulting pressure on the wiper causes the latter to yield against its spring and swing on its pivot to some such 50 position as that shown in dotted lines in Fig. 2, thereby permitting the jammed crown to be released.

While the wiper 66 has been shown as 55 being close to the chute it is to be understood that the invention includes crown wiping means having other locations beyond the chute.

In the structure shown, the capping mechanisms are described as moving in a counter-clockwise direction (Fig. 2). Since rotation in the opposite direction may occur, means is provided for mounting the wiper for operation in either direction. To this 60 65 end, in the embodiment illustrated, the

bracket 69 has two bearing sleeves for the pivotal pin 67, these being symmetrically located with respect to the chute mouth as appears more clearly in Figs. 4 and 7. The pivotal pin may be located in either bearing 70 and, as will be apparent, the sleeve 75 is readily reversible in its socket 77. With these changes made, the wiper is available for opposite rotation of the capping mechanisms. 75

As before described, when compensation takes place with respect to the plunger in capping position, there is a slight upward movement of the other plungers. Should a bottle fail to have been centrally registered 80 with the capping mechanism, it sometimes happens that such a bottle is caught under the lower edge of the descending throat carrier. When this occurs, excessive compensation takes place with a correspondingly 85 greater rise of the other plungers, earlier in the cycle than ordinarily takes place. It may happen, therefore, that the particular plunger in cap receiving position starts to rise before the lip 52 of the bell-mouthed 90 platform 16 has passed out from under, and cleared the wiper 66.

The invention in its entirety includes means whereby the wiper is yieldable in a vertical direction, and in structures embodying the invention to the best advantage the bracket which carries the wiper is yieldably mounted on a horizontal pivot. Although capable of various constructions, in the one illustrated, the bracket 69 is provided with 100 arms 78 which are pivotally mounted on pins 79 carried by the supporting arm 61. Downward movement of the bracket is limited by its engagement with the supporting arm 61, as appears in Fig. 7, and upward 105 movement is yieldably opposed as follows: The eye socket 77 of the bracket 69 is provided with a cam face 81 engaged by a plunger 82 pressed thereagainst by a spring 83 inclosed in a sleeve 84 which is threaded 110 through an eye socket 85 on the supporting arm 61. The other end of the spring bears against a thumb nut 86 at the end of the sleeve and the spring pressure is adjustable by means of the movement of the sleeve in 115 the socket.

Should a particular capping plunger start to rise prematurely, that is to say, before the wiper is cleared, the engagements of the lip of the flaring platform 16 against 120 the wiper causes the latter to yield by swinging up the bracket 69 on its pivot, this movement of the wiper permitting the platform 16 to pass on in its orbital movement. As soon as the parts have cleared, the bracket 125 returns to normal position under the force of its spring.

As will be apparent from the drawings, the terminal lip 65 of the chute extends into the orbital path of the capping mechanism 130

but is normally cleared by virtue of the recessed formation (Fig. 3). Means is provided, however, for yieldably mounting this lip, so that it will give way in case it is engaged by any portion of the relatively moving parts of the machine. To this end, in the present embodiment the lip 65 is formed as a stepped up portion of a circular plate 88 which bears against the bossed bottom of block 63, the lip fitting about the boss. This plate 88 is pivotally mounted on a stud 89 extending downward from the block 63, and is held in place by a nut 90 and lock nut 91. As shown more clearly in Fig. 5, the lip 65 is thus flush with that portion of the crown passage formed by block 63 and at the same time it is movable relatively thereto. When the lip 65 is in normal crown-feeding position, a lip 92 on plate 88 bears against a stop pin 93 on block 63 and the parts are yieldably held in this position as follows: Bearing against a stud 94 on the plate 88 is a plunger 95 cut away (Fig. 7) to clear the other parts and pressed against the stud by a spring 96 inclosed in a sleeve member 97 formed on the bottom of the supporting arm. The other end of the spring bears against an adjusting nut 98 threaded into the sleeve, the spring pressure being adjustable by means of movement of this nut. Should lip 65 be engaged by any portion of the relatively moving parts of the machine, the pressure on the lip causes the stud 94 to displace the plunger 95 against its spring, the lip swinging to some such position as that shown in dotted lines in Fig. 8. As soon as the interfering part has cleared, the lip returns to its normal position under the force of its spring.

40 Since the interfering part may engage the lip on either side, depending on the orbital direction of the capping mechanism, means is provided whereby the lip may be mounted to yield in either direction. As here shown, 45 the supporting arm is provided with two sleeves 97, the plate 88 has two studs 94 and the block 63 has two holes 99 for the stop pin 93, these parts being respectively symmetrically located with respect to the central 50 line of the crown passage. In case the orbital direction of the capping mechanism is changed, it is merely necessary to shift the stop pin to the other hole 99 and to transfer the plunger 95, spring 96 and nut 98 to 55 the other sleeve.

The structure described, then, comprises crown-supplying means, such that uncentered crowns are positively forced into position; such that the positioning wiper 60 yields horizontally to release jammed crowns and vertically to allow a premature elevated capping mechanism to clear; and such that the terminal lip of the chute is yieldable upon interference with any portion of the 65 moving parts. Further, the structure is

such that these features are readily available for use with capping mechanism having its orbital movement in either direction of rotation.

Although the term "crown" has been used throughout to designate the caps, it is understood that this term is used merely as an exemplification and that the invention is not limited to any particular type of cap.

What is claimed is:

1. In bottle capping apparatus, a crown feeding chute, capping mechanism having an orbital movement with respect to said chute, a throat carrier having a crown platform included in the capping mechanism and formed with an opening registering with the crown passage of the chute, whereby crowns flow from the chute into said platform, and means beyond the chute for positively acting on the crowns to move the same into position in said platform. 75

2. In bottle capping apparatus, a crown feeding chute, capping mechanism having an orbital movement with respect to said chute, a throat carrier having a crown platform included in the capping mechanism and formed with an opening registering with the crown passage of the chute, whereby crowns flow from the chute into said platform, and means beyond the chute for wiping crowns into centered position in the platform. 90

3. In bottle capping apparatus, a crown feeding chute, capping mechanism having an orbital movement with respect to said chute, a throat carrier having a crown platform included in the capping mechanism and formed with an opening registering with the crown passage of the chute, whereby crowns flow from the chute into said platform, and a wiper beyond the chute located in the path of uncentered crowns to cause the same to be centered in the platform. 100

4. In bottle capping apparatus, a crown feeding chute, capping mechanism having an orbital movement with respect to said chute, a throat carrier having a crown platform included in the capping mechanism and formed with an opening registering with the crown passage of the chute, whereby crowns flow from the chute into said platform, and a wiper beyond the chute located in the path of uncentered crowns to cause the same to be centered in the platform, said wiper being yieldable to release a jammed crown. 110

5. In bottle capping apparatus, a crown feeding chute, capping mechanism having an orbital movement with respect to said chute, a throat carrier having a crown platform included in the capping mechanism and formed with an opening registering with the crown passage of the chute, whereby crowns flow from the chute into said 125

platform, a yieldable member associated with the platform arranged to engage a crown to hold it in place, and means for positively acting on the crowns to move the 5 same into position in said platform.

6. In bottle capping apparatus, a crown feeding chute, capping mechanism having an orbital movement with respect to said chute, a throat carrier having a crown platform included in the capping mechanism and formed with an opening registering with the crown passage of the chute, whereby crowns flow from the chute into said 10 platform, a yieldable member associated with the platform arranged to engage a crown to hold it in place, and means for wiping crowns into centered position in the 15 platform.

7. In bottle capping apparatus, a crown feeding chute, capping mechanism having an orbital movement with respect to said chute, a throat carrier having a crown platform included in the capping mechanism and formed with an opening registering 20 with the crown passage of the chute, whereby crowns flow from the chute into said platform, a yieldable member associated with the platform arranged to engage a crown to hold it in place, and a wiper beyond the chute located in the path of uncentered crowns to cause the same to be centered in the platform.

8. In bottle capping apparatus, a crown feeding chute, capping mechanism having an orbital and a vertical movement with respect to said chute, a throat carrier having a crown platform included in the capping mechanism and formed with an opening registering with the crown passage of the 35 chute, a wiper located in the path of uncentered crowns for causing the same to be moved into position in the platform, a portion of the capping mechanism moving in a path below said wiper, and means for 40 mounting the wiper to permit the same to yield vertically.

9. In bottle capping apparatus, a crown feeding chute, capping mechanism having an orbital and a vertical movement with respect to said chute, a throat carrier having a crown platform included in the capping mechanism and formed with an opening registering with the crown passage of the chute, and a wiper for moving crowns into 45 position in the platform, said wiper being yieldable horizontally and vertically.

10. In bottle capping apparatus, a crown feeding chute, capping mechanism having an orbital and a vertical movement with respect to said chute, a throat carrier having a crown platform included in the capping mechanism and formed with an opening registering with the crown passage of the chute, a wiper located in the path of uncentered crowns for causing the same to be 55

moved into position in the platform, a portion of the capping mechanism moving in a path below said wiper and a vertically yieldable bracket for carrying said wiper.

11. In bottle capping apparatus, a crown feeding chute, capping mechanism having an orbital movement with respect to said chute, and a lip yieldable in the direction of such orbital movement associated with said chute to form a terminal thereof and to extend into the orbital path of the capping mechanism.

12. In bottle capping apparatus, a crown feeding chute, capping mechanism having an orbital movement with respect to said chute, a lip yieldable in the direction of such orbital motion associated with said chute to form a terminal thereof, and means for normally holding said lip in crown feeding position.

13. In bottle capping apparatus, a crown feeding chute, a terminal lip associated therewith, means for mounting said lip to yield in one direction in a substantially horizontal plane, and means for mounting the lip to yield in the opposite direction.

14. In bottle capping apparatus, a crown feeding chute, capping mechanism having an orbital and a vertical movement with respect to said chute, a wiper beyond the chute located in the path of uncentered crowns to cause the same to be centered in the platform, and means for mounting said wiper on either side of said chute.

15. In bottle capping apparatus, a crown feeding chute, capping mechanism having an orbital movement with respect thereto, a crown centering latch, a pivotal pin on which said latch is mounted, a spring pressed member for yieldably holding said latch and pivot in normal position, and means for adjusting the force of said spring.

16. In bottle capping apparatus, a crown feeding chute, capping mechanism having an orbital movement and a vertical movement with respect thereto, a crown centering latch, a pivotal pin on which said latch is mounted, a spring pressed member for yieldably holding said latch in normal position, a pivotally mounted bracket for carrying said latch and its pivot, and means for yieldably holding said bracket in normal position.

17. In a bottle capping apparatus, a crown feeding chute, capping mechanism moving past said chute, a throat carrier having a crown platform included in the capping mechanism and formed with an opening registering with the crown passage, whereby crowns flow from the chute into said crown platform, and a crown wiper beyond the chute having a crown guiding face substantially parallel with the chute and a crown wiping face oblique to the chute.

18. In a bottle capping apparatus, a crown feeding chute, capping mechanism moving past said chute, a throat carrier having a crown platform included in the capping mechanism and formed with an opening registering with the crown passage, whereby crowns flow from the chute into said crown platform, and a yieldably mounted crown wiper beyond the chute having a 10 crown guiding face substantially parallel with the chute and a crown wiping face oblique to the chute.

19. In bottle capping apparatus, a crown feeding chute, capping mechanism having an 15 orbital movement with respect to said chute, a yieldable crown centering wiper, means in-

cluding a spring for holding said wiper in normal position, and means for adjusting the force of said spring.

20. In bottle capping apparatus, a crown 20 feeding chute, capping mechanism having an orbital movement with respect to said chute, a pivotally mounted crown centering wiper, means including a spring for holding said wiper in normal position, and means 25 for adjusting the force of said spring.

In testimony whereof, I have hereunto set my hand.

SAMUEL W. TAYLOR.

Witnesses:

B. T. TENNISON,
L. W. WINSLOW.

It is hereby certified that in Letters Patent No. 1,392,980, granted October 11, 1921, upon the application of Samuel W. Taylor, of Baltimore, Maryland, for an improvement in "Bottle-Capping Apparatus," an error appears in the printed specification requiring correction as follows: Page 3, line 45, for the word "each" read *such*; and that the said Letters Patent should be read with this correction therein that the same may conform to the record of the case in the Patent Office.

Signed and sealed this 22d day of November, A. D., 1921.

[SEAL.]

WM. A. KINNAN,

Acting Commissioner of Patents.
